United States Patent Office.

ALVAH RITTENHOUSE, M. D., OF PHILADELPHIA, PENNSYLVANIA.

Letters Patent No. 82,349, dated September 22, 1868.

IMPROVED FEMALE-SYRINGE BED-PAN.

The Schedule referred to in these Letters Patent and making part of the same.

TO ALL WHOM IT MAY CONCERN:

Be it known that I, ALVAH RITTENHOUSE, M. D., of the city and county of Philadelphia, and State of Pennsylvania, have invented a new and improved Female-Syringe Bed-Pan; and I do hereby declare that the following is a full and exact description thereof, reference being had to the accompanying drawing, making a part of this specification, in which—

Figure 1 is a vaginal metallic tube. Letter A, the end to be connected with a rubber tube.

Figure 2, a rubber tube, by which the vaginal tube may be lengthened or shortened at pleasure, to suit the patient, by sliding it out and in the said rubber tube. Letter B, the end of the rubber tube, which is connected to fig. 3 at letter C.

Figure 3, a metallic tube. Letter C, the end to be inserted into the rubber tube, at which there is an outlet-valve; letter D, the top to be inserted into the rubber bulb; letter E is an inlet-valve.

Figure 4 is a short-angle suction-tube, with inlet-valve at letter F. It is to be placed inside of the capsular vulva at letter K, fig. 6.

Figure 5, a rubber bulb, to be placed on top of tube, fig. 3, at letter D.

Figure 6, a bed-pan or vessel to hold any medicated preparation. Letter H, an artificial capsular vulva; letter J, the body of the vessel, round in shape, similar to a fruit-can, to hold a quart, more or less; letter I, an opening for a cork, by which the vessel is filled inside of the capsular vulva; letter K, the suction-tube with valve.

Figure 7, the several parts combined, making a complete "female-syringe bed-pan," to be used for injecting into the vagina and uterus any medicated preparation in severe cases of flooding, or uterine hemorrhages, without moving the patient, therein having a great advantage and merit over all other appliances.

The fluid is first put in the vessel, the vaginal tube, fig. 1, into the vagina, and gently pressed till the capsular vulva comes in contact with the vulva. As the fluid is then thrown into the vagina or uterus, as the case may be, it passes out, and is sucked up by suction-tube, letter K, fig. 7, thereby avoiding any leakage. It can also be used in any position, sitting, standing, or lying, with perfect ease, without any leakage, by the patient or nurse.

Letter L is a perforated strainer, by which all the fluid is perfectly cleared of all sediment before entering the syringe-tube, thereby keeping the valves in perfect working order.

What I claim, and desire to secure by Letters Patent, is—

1. The bed-pan or vessel J, capsular vulva H, right-angle suction-tube K, substantially as set forth.
2. The vaginal extension-tube N O, metallic valve-tube P, right-angle suction-tube K, rubber bulb R, vessel J, capsular vulva H, strainer L, all combined and arranged substantially in the manner and for the purpose as herein set forth and described.
